UNITED STATES PATENT OFFICE.

WILLIAM H. OLVER, OF OSHKOSH, WISCONSIN.

IRONING-MACHINE.

1,207,201.

Specification of Letters Patent.

Patented Dec. 5, 1916.

Application filed April 12, 1916. Serial No. 90,558.

To all whom it may concern:

Be it known that I, WILLIAM H. OLVER, a citizen of the United States, and resident of Oshkosh, in the county of Winnebago and State of Wisconsin, have invented certain new and useful Improvements in Ironing-Machines; and I do hereby declare that the following is a full, clear, and exact description thereof.

10 The present invention relates to new and useful improvements in ironing machines wherein a partial support for the iron is had to relieve the operator of unnecessary lifting strain in manipulating the iron, and 15 the invention is directed more particularly to machines of the type embodied in Patent No. 902673 granted to me November 3rd, 1908, and Patent No. 1082548 granted to me December 30th, 1913.

20 Pressing operations are usually conducted on a table surface on which is normally positioned a pressing board or buck and in differing instances it is desirable to press upon either the table surface or upon the pressing 25 board surface. Also it is often found expedient to employ a pad on the pressing board. Thus a considerable vertical adjustment of the iron for pressing operations in conjunction with these different surfaces is 30 necessary. However, the pressing board surface is the one usually employed.

Pressing operations require a very frequent shifting of the iron to and from a position of rest, to permit manipulation of the 35 material being pressed, and the greatest element of strain in pressing operations resides in the lifting of the iron from its normal position of rest to its operative position with respect to the pressing board, in successive 40 pressing movements.

It is therefore primarily an object of the present invention to provide a structure hereby obviating the necessity of lifting the iron in 45 moving it from its normal position of rest, obviating in a manner however which does not interfere with the efficient operative manipulation of the iron.

Another object is to provide a structure herein a maximum degree of adjustment 50 and a maximum readiness of vertical adjustment of the iron may be procured with respect to the support member.

It is also an object to provide a means 55 normally urging the iron to a position of rest at one side of the apparatus.

Another object resides in the provision of

a means for securing the iron to the supporting member in such manner that free universal movement of the iron may be had, this arrangement being procured without 60 interference in gripping the iron for manipulation thereof.

It is further an object to provide a structure wherein desired lateral play of the iron may be permitted.

It is still further an object to compass the aforementioned objects in a structure wherein the various parts coact in a manner conducive to a maximum simplicity of structure.

With the above and other objects and advantages in view, the invention resides more particularly in the novel combination, arrangement, and formation of parts more particularly hereinafter described and more particularly pointed out in the appended claims.

In the drawings: Figure 1 is an elevational view of my improved ironing machine. Fig. 2 is a vertical longitudinal sectional view through the suspension carriage, this view being taken on the line 2—2 of Fig. 1. Fig. 3 is a vertical sectional view through the resilient support of the track rail on the line 3—3 of Fig. 1. Fig. 4 is a detailed sectional view taken vertically through one of the track wheels on the line 4—4 of Fig. 1. Fig. 5 is a detailed sectional view showing the means for securing the sections of the suspension bar together. Fig. 6 is an enlarged detailed view of the lower end of the suspension bar, this view being taken also on the line 2—2 of Fig. 1. Fig. 7 is a detailed sectional view showing the means for connecting the carriage suspension spring to the suspension bar.

Referring now more particularly to the accompanying drawings, 5 designates the top of a pressing table or other support, and 6 designates a pressing board of a conventional type disposed on one end thereof.

My improved ironing machine comprises a pair of end uprights 7 extending from sockets 8 provided at the side portions of the table and each standard is provided with a pair of forwardly extending spaced bracket arms 9 which carry at their forward ends a bar 10 which is engaged in a respective end opening 11 of a track rail 12 on which is slidably mounted the suspension carriage. These bracket arms may be of any desired construction and are preferably attached to

the standards in such manner that they may be adjusted vertically thereon, although other means are provided for procuring a desired adjustment of the iron with respect 5 to the table. The upper bracket arm of the standard 7 adjacent the pressing board 6 is raised above the corresponding bracket arm of the other standard and the track rail is mounted on the bar below the first mentioned bracket arm and above the second mentioned bracket arm and an expansive spring 13 surrounds the bar 10 of the first mentioned bracket arm and bears against the track rail and against the respective 10 lower bracket arm to thus normally urge the rail to assume an inclined position as is shown in Fig. 1, the openings 11 of the track rail being of such size as to provide a desired looseness to permit a certain pivotal 15 movement of the track rail on the rod 10 of the standard farthest from the pressing board. The function of this arrangement will be later described.

The suspension carriage member comprises a pair of normally vertically disposed side bars 14 having their upper ends connected by a bolt 15 and held spaced by a sleeve 16 on the bolt, and this bolt is also passed through the intermediate portions of 20 a pair of transverse wheel bars 17. Bolts 18 on which are mounted intermediately disposed sleeves 19, are passed through the ends of these bars and mounted on the sleeves are the wheels 20 which ride in a longitudinal groove 21 in the track rail 12. Thus the carriage is suspended in a manner permitting free universal pivotal movement with respect to the track rail, as the side bars of the carriage are spaced from the 25 track rail a sufficient distance to permit a tilting of the wheels to procure transverse pivotal movement. A strip 22 connects the lower end of the bars 14, and slidably passed through this strip is the upper sleeve section 23 of a suspension rod including the lower section 24 telescopically engaged in the said sleeve section. A retractile spring 25 has its upper end secured to a cross brace at the upper portion of the bars 14, this cross- 30 brace including a bolt 26 passed through the bars and a spacing sleeve 27 on the bolt. The lower end of the spring is secured to a nut 28 which is threaded on the upper end of the sleeve section 23. The sections of the 35 suspension rod are adjustably held together by a set screw 29 passed through a bearing block 30 on the lower end of the sleeve section 23 and passed through said section to bindingly engage the section 24.

40 31 designates the conventional type of iron which is associated with the pressing machine and which is provided with the usual handle 32 disposed horizontally thereover. For securing the suspension rod to the iron in a manner not interfering with a

proper gripping of the handle 32 by the operator, and further in a manner permitting free universal pivotal movement of the iron with respect to the suspension rod, a bowed arm 33 is pivoted to a bifurcated attaching sleeve 34 secured at the lower end of the suspension rod section 24 and the lower end of this arm extends laterally under the handle of the iron and engages in an upstanding apertured ear 35 provided on the iron at the central portion of its top. This laterally extending arm portion is provided with a notch 36 receiving the outer portion of the ear, and is of greater width than the aperture of the ear, and curved at its extremity whereby accidental detachment of the iron is prevented, attachment and detachment of the iron being procured by swinging the iron relative to the arm.

In the foregoing description a structure 45 has been set up which is of maximum simplicity and which provides a maximum and exceedingly ready and efficient operation.

The iron may be adjusted vertically by sliding the suspension rod section 34 in the sleeve section 23 and it is noted that a maximum degree of adjustment is provided for inasmuch as the section 24 may extend upwardly entirely through the section 23 so that its upper end lies within the spring 25.

Fig. 1 shows the carriage and iron in an intermediate position of movement toward the pressing board 6. In its normal position of rest the carriage is at its extreme limit of movement to the right hand side of the machine and the securing nut 28 of the suspension spring 25 rests on the transverse bottom bar 24 of the carriage whereby the iron is held with its pressing face slightly below the pressing face of the board 6. In moving the iron to operative position on the board, it is elevated during such movement in consequence of the inclination of the track rail 12, and thus it slides readily onto the adjacent end of the board 6 in such movement. When the iron is disposed over the board 6, the leverage exerted on the track is increased with respect to the spring 100 18 and the spring yields to a considerable extent, which permits a retraction of the spring 25 to lift the nut 28 from the bottom bar 24 of the carriage and thus a lateral play of the iron in a horizontal plane is permitted, it being noted that were this arrangement not provided and the nut not permitted a vertical play during the pressing action, lateral movement of the iron would swing it necessarily in an arc and thus prevent proper operation. At the extreme right hand end of the pressing board the normal position of the bottom face of the iron would be slightly below the plane of the upper face of the board. However, the momentum imparted to the iron in a sweeping movement on to the board, would be such that the bot- 110 115 120 125 130

tom face of the iron would be disposed above the board in such movement, it being also noted that a slight tipping of the iron would facilitate its movement onto the board should 5 the bottom face of the iron not attain a sufficient height during such movement. When the iron is at and adjacent its position of rest, its leverage exerted on the spring is comparatively slight and the spring holds 10 the track in an inclined position whereby the carriage is urged by gravity to hold the iron in said position of rest.

Thus, the present arrangement, in addition to eliminating the necessity of any lifting action in moving the iron from its position of rest, also eliminates the provision of a bracket support or stand for the iron in said position, and the effort incidental to 15 properly positioning the iron on such support. To adapt the iron for pressing either on the table surface or on the pressing board surface, or on a pad on the board, the adjustment of the sleeve and rod sections 20 and 24 respectively is utilized.

25 I claim:

1. An ironing machine comprising a track rail, means affording a pivotal fixed support

for the rail at one end, means resiliently supporting the rail at its other end in a position inclined upwardly toward said end, a 30 suspension carriage mounted on the track rail, an iron carrying suspension bar resiliently connected with and depending from the carriage and means limiting the downward movement of the bar with respect to 35 the carriage.

2. In an ironing machine, the combination of a track rail, a suspension carriage mounted on the rail, a sleeve slidably connected with the carriage, a retractile coil 40 spring secured to the sleeve and to the carriage, a bar slidably adjustable in the sleeve and extensible into the spring and means carried by the said bar for attachment of an iron thereto.

In testimony that I claim the foregoing I have hereunto set my hand at Milwaukee, in the county of Milwaukee and State of Wisconsin, in the presence of two witnesses.

WILLIAM H. OLVER.
